UNITED STATES PATENT OFFICE.

ALEXANDER C. DECKER AND OLIVE J. DECKER, OF KEOKUK, IOWA; SAID
OLIVE J. DECKER ASSIGNOR TO JAMES AYRES AND PETER AYRES, OF
SAME PLACE.

BUSTLE.

SPECIFICATION forming part of Letters Patent No. 374,660, dated December 13, 1887.

Application filed October 17, 1887. Serial No. 252,603. (No model.)

To all whom it may concern:

Be it known that we, ALEXANDER C. DECKER and OLIVE J. DECKER, of Keokuk, in the county of Lee and State of Iowa, have invented 5 certain new and useful Improvements in Bustles, of which the following is a specification.

This invention relates to bustles, and has reference to a novel construction of the frames thereof.

10 In the drawings, Figure 1 is a perspective view of our improved bustle with some of the tapes, attaching -straps, &c., omitted; Figs. 2 and 3, side views illustrating slightly different forms of the invention, and Figs. 4 and 5 15 views illustrating the manner of securing the tapes in position.

We desire to state here that we are aware 20 that it has been proposed to provide the upright arms of bustle - frames with a series of coils or eyes, (arranged in a substantially upright position,) one above another, to receive the ends of the bows and to compensate for or 25 permit the folding of the bustle-frame, and it is to overcome some of the objections to such a construction that the present invention is designed.

The bustle-frame proper is made of a single 30 piece of wire bent to form a horizontal bow, *a*, and upright arms *b b*. The arms *b b* are formed by bending or twisting the wire in the form of a helix, *c*, the ends *d* of the wire, or that portion of the arms above the helix, being carried to the opposite side of the bustle - frame and connected with its opposing arm *b* or with 35 the bow *a* near the base of the arm. In Fig. 1 the ends *d* of the wire cross at the middle of the top, and, after being united at that point by the tape or tapes *e*, they are connected with or secured to the uppermost coil of the helix 40 *c* of the opposing arm.

In Fig. 2 the ends *d* project downwardly through the majority of the coils of the helix, and are made fast to one of the lower coils, while in Fig. 3 the ends *d*, instead of connecting with the lower coils, as in Fig. 2, extend 45

entirely through the series, are bent to form a coil or helix, *f*, and are attached to the bow *a* near the base of the arms *b b*. This construction of the frame proper permits folding of the bustle, and besides being much stiffer 50 is easier and cheaper to make than the frames to which we have before referred.

The bows *g* may be connected with the bends or coils of the helix, as in Figs. 1 and 3, or to the ends *d d* of the arms, as in Fig. 2. 55

Upon reference to Figs. 4 and 5 it will be noticed that the wires are indented or offset slightly, as at *h*, where the tapes pass over or about them, so that when the tapes are fastened to the wires by the pronged plates *i* any 60 slipping or lateral movement of the tapes upon the wire is prevented.

Having thus described our invention, what we claim is—

1. A bustle-frame comprising the bow *a* and 65 upright helical arms *b b*.

2. A bustle-frame comprising a horizontal bow, *a*, and upright arms, the ends or extensions *d* of the arms being carried to opposite sides of the bustle-frame and secured to the 70 upright arms, substantially as shown.

3. The herein-described bustle-frame, comprising horizontal bow *a*, arms *b b*, having each a helix, *c*, extensions *d d*, extending from the upper ends of the helices to the opposite 75 side of the bustle, and bows *g g*, all combined substantially in the manner shown.

4. The herein-described bustle, comprising bow *a*, arms *b b*, provided with helices *c*, an extension, *d*, extending from each arm and secured to the opposite arm and provided with a helix, *f*, and bows *g*, all arranged substantially as described. 80

In witness whereof we hereunto set our hands in the presence of two witnesses.

ALEXANDER C. DECKER.
OLIVE J. DECKER.
